Des. 205,044
Patented June 14, 1966

205,044

LAUNDRY AGITATOR

James A. Tichenor, St. Joseph, Mich., assignor to Whirlpool Corporation, a corporation of Delaware

Filed Sept. 15, 1965, Ser. No. 86,996

Term of patent 14 years

(Cl. D49—1)

The agitator is symmetrical about a vertical axis.

I claim:

The ornamental design for a laundry agitator, as shown and described.
